UNITED STATES PATENT OFFICE.

LEWIS C. SPRINGER, OF WILMINGTON, DELAWARE.

GRINDING-MILL.

SPECIFICATION forming part of Letters Patent No. 290,369, dated December 18, 1883.

Application filed June 27, 1883. (No model.)

To all whom it may concern:

Be it known that I, LEWIS C. SPRINGER, of Wilmington, in the county of New Castle and State of Delaware, have invented certain new and useful Improvements in Grinding-Mills; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved grinding-mill. Fig. 2 is a vertical sectional view of the same. Fig. 3 is a horizontal sectional view of the same on line *x x* in Fig. 2. Fig. 4 is a similar view on line *y y* in Fig. 2. Fig. 5 is a cross-sectional view of the spindle, taken on line *z z*, Figs. 1 and 2. Fig. 6 is a partial vertical sectional view in a plane longitudinally of the bridge-tree; and Fig. 7 is a horizontal sectional view of the sleeve *E*, showing the corrugations of the plates on its internal surface.

Similar letters of reference indicate corresponding parts in all the figures.

My invention has relation to improvements in grinding-mills; and it consists in the improved construction and combination of parts of the same, as hereinafter more fully described and claimed.

In the accompanying two sheets of drawings, *A* represents the bed-plate of the mill.

B represents metal posts or standards, bolted at their lower ends to the bed-plate, and at their upper ends to the sides of the cylindrical grinding-chamber *C*.

D represents the hopper, which is provided at its top with a suitable bearing, *I*, to receive the upper end of the spindle *K*, and is connected at its lower end by means of a flange-joint to the top of a collar, *E*, on the top of the cylindrical grinding-chamber *C*; the flange of the collar being recessed at *K'* for the reception of gates *F*. The outer ends of the gates *F* are bent down at right angles, each gate being provided with an adjusting-screw, *G*, passing through a slot or opening in the bent end of the gate, the point of the screw entering the side of the collar *E*.

It will be seen that by turning the screws *G* the gates *F* will be advanced or retracted, so as to regulate the amount of grain or other material which passes from the hopper into the cylindrical grinding-chamber *C*. A spiral spring, *H*, is placed around each of the screws *G*, between the bent end of the gate, through which the screw passes, and the side of the collar, and serves to hold the gate open.

K represents the spindle, which is secured at its upper end in a bearing, *I*, the toe of the spindle resting in the socket or step *J*, which is vertically adjustable in the manner hereinafter described. A metal disk, *L*, is secured to the spindle by bolts passing through a collar, *M*, cast on its lower side. This disk supports the runner *N*, which is cast of steel. The grinding-plate *O* is also made of steel, and the grinding-plates are fastened (the runner to the disk *L*, and the stationary one to the disk *M*) forming the top of the grinding-chamber by bolts *N'*, passing through the disks and the grinding-plates.

The dress of the runner (shown at Fig. 4) consists of a series of curved furrows, *P*, running from the central bushing of the runner to its periphery, each alternate quarter having a recess, *Q*, for the reception of the head of the bolts *N'*. The other alternate quarters have each a straight branch furrow, *L'*, which intersects the curved leader at *R*, and extends from this point of contact to the periphery of the runner. The grinding-face of the grinding-plate is dressed in a similar manner.

The serrated grinding-surface of the hopper *D* consists of a steel casing, *S*, which fits inside of the hopper, and is held in place by bolts *T*. This serrated casing *S* is cast in sections, so that when one of the sections becomes worn it can be removed and replaced by another without removing the entire casing. The serrated grinding-surface of the collar *E* (shown at Fig. 7) also consists of a steel casing, *U*, cast in sections, and fastened to the inner surface of the collar by means of bolts *V*. A series of breaker-disks, *W*, are fastened upon the spindle, and extend from a point slightly above the bottom of the collar *E* to a point opposite the top of the hopper. A collar, *X*, is bolted upon the spindle above the breaker-disks, and serves to

to prevent all longitudinal motion of the said disks. The spindle may be made square, in which case the eyes of the disks W are also made square, to fit the shape of the spindle; or 5 the spindle may be made round, in which case it has a feather, Y, consisting of a metal slip inserted longitudinally into the spindle and projecting therefrom, so as to fit into a groove, Z, in the eye of each of the disks W, as clearly 10 shown in Fig. 5 of the drawings. The breaker-disks are adjusted upon the spindle in such a manner that their teeth break joints with each other, as shown in Fig. 5, where A' represents the teeth of the top breaker-disk, and B' the 15 teeth of the disk immediately below it.

C' represents wings, of leather or other suitable material, which are attached to the under side of the metal disk L for the purpose of sweeping the ground meal into the discharge-spout D'. 20 E' represents a metal sleeve, which is provided with a flange, F', by which it is secured to the bed-plate A. The step J, (shown at Fig. 2,) which supports the toe of the spindle, is inserted into this sleeve, the bottom of the 25 step resting upon a bridge-tree, G', which passes through the sleeve. The bridge-tree G' is provided at each of its ends with a lighter-screw, H', so that by turning the screws H' the spindle can be raised or lowered, so as to diminish or increase the distance between the 30 grinding-surfaces of the mill-plates N and O. To the bottom of the cylindrical grinding-chamber C is bolted a bearing, I', through which the spindle passes, and which acts as a brace 35 for the lower part of the spindle.

K' represents a pulley-wheel attached to the end of a drive-shaft which is hung in suitable bearings, the said shaft having a bevel-pinion, J', on its inner end, gearing into a 40 bevel-pinion, J'', on the spindle.

The grain or other material is put into the hopper, where it is partially broken between the surfaces of the breaker-disks and the serrated grinding-surfaces of the hopper and col-

lar E. The grain is then fed to the grinding- 45 plates through the eye of the bed-plate O, and after being thoroughly ground falls to the bottom of the cylindrical grinding-chamber C, when the wings C' sweep the ground meal into the discharge-spout D'. 50

From the foregoing description, taken in connection with the accompanying drawings, the operation of my improved grinding-mill will readily be understood without requiring extended explanation. 55

If it is desired to use the mill without the breaker attachment, the serrated inner surface of the hopper and the collar E can be readily removed by unscrewing the bolts which hold the steel sections in position, and by removing the collar X from the spindle the breaker-disks W can be readily removed from the spindle. 60

Having thus described my invention, I claim and desire to secure by Letters Patent of the 65 United States—

1. In a grinding-mill, the combination of the flanged hopper D, flanged collar E, having recesses K', gates F, sliding in said recesses in the flange of the collar, adjusting-screws G, and 70 spiral springs H, encircling said screws, and adapted to hold the gates in an open position, substantially as and for the purpose shown and set forth.

2. The herein-described millstone-dress, 75 consisting of the reversely-curved furrows P, running from the eye of the stone to its periphery, and intersected by straight branch furrows L', running from the point of contact R to the periphery of the plate or stone, substantially 80 as and for the purpose shown and described.

In testimony that I claim the foregoing as my own I have hereunto affixed my signature in presence of two witnesses.

LEWIS C. SPRINGER.
